UNITED STATES PATENT OFFICE.

MATTHIAS B. EATON, OF BOSTON, MASSACHUSETTS, ASSIGNOR TO JAMES C. CAMERON, OF MONTREAL, CANADA.

TRACK-CLEARER.

SPECIFICATION forming part of Letters Patent No. 625,438, dated May 23, 1899.

Application filed October 27, 1898. Serial No. 694,660. (No model.)

To all whom it may concern:

Be it known that I, MATTHIAS B. EATON, a citizen of the United States, residing at Boston, in the county of Suffolk and State of Massachusetts, have invented certain new and useful Improvements in Track-Clearers; and I do hereby declare the following to be a full, clear, and exact description of the invention, such as will enable others skilled in the art to which it appertains to make and use the same.

My invention relates to improvements in track-clearers. Each clearer is designed to act whichever way the train is moving. It is designed to throw all the material which may be on the rail outwardly whichever way the train is moving. It is also designed to remove what may be in front of the truck, as well as anything that may happen to be left by the front clearer or which may fall back upon the rail after the trucks have passed.

In the drawings herewith accompanying and making a part of this application, Figure 1 is a side elevation of a truck having my improved clearer attached thereto. Fig. 2 is a perspective detail view of the clearer; and Fig. 3 is an inverted plan view of the clearer and a section of the rail, the rail showing in dotted lines.

In said drawings, A represents a truck-frame, and B the trucks. The clearer consists of the supporting-bar C, secured to the truck-frame by means of bolts D. The clearer proper is made integral with the supporting-bar and consists of a double moldboard E, having a common outer edge E', which extends at right angles to the track and at the bottom lies beyond the outside of the rail. The back edges F of the moldboard extend beyond the inside of the track, as indicated in Fig. 3. The

clearer extends down to a point near the top 40 surface of the rail, thus extending from a point inside the rail to a point outside thereof to completely clear the way for the trucks.

The advantages of my improved clearer are that the first one removes the snow or other 45 material from the rail in front of the trucks, and the second one, attached to the rear of the truck-frame, removes any material that may chance to fall back on the rail after the truck has passed, thus making the complete 50 removal of the snow or other obstruction doubly certain. Another advantage is that each clearer operates whichever direction the train is moving.

My improved clearer may be applied to the 55 trucks of snow-plows, engines, or cars.

Having thus described my invention and its use, I claim—

1. A track-clearer having a double moldboard and a common edge, said common edge 60 extending outside the rail and said moldboards extending diagonally across the rail, whereby each moldboard throws outside the rail, and means for securing said clearer to the truck-frame. 65

2. A track-clearer having a double moldboard and a common edge, said common edge extending beyond the outside edge of the rail and the heel of both moldboards extending beyond the inside edge of the rail, and means 70 for securing said clearer to the truck-frame.

In testimony whereof I affix my signature, in presence of two witnesses, this 12th day of October, 1898.

MATTHIAS B. EATON.
